UNITED STATES PATENT OFFICE.

WALTER T. PUTNAM, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

VARIABLE-SPEED-DRIVING MECHANISM FOR CONDENSERS.

Application filed June 28, 1924. Serial No. 723,063.

To all whom it may concern:

Be it known that I, WALTER T. PUTNAM, a citizen of the United States, and resident of North Andover, county of Essex, State 5 of Massachusetts, have invented an Improvement in Variable-Speed-Driving Mechanism for Condensers, of which the following description, in connection with the accompanying drawing, is a specification, like 10 characters on the drawing representing like parts.

This invention relates to the driving mechanism of a condenser preferably of the apron type which is employed for condensing the stock doffed from a carding machine into roving:

The object of the invention is to provide simple and efficient means for readily effecting such variation in the speed of the 20 driving mechanism as is necessary to accommodate the machine for handling a wide range in the grades of material.

The nature and objects of the invention will appear more fully from the accompanying specification and drawings and will be 25 particularly pointed out in the claims.

In the drawings:

Fig. 1 is a side elevation chiefly in diagrammatic form of a portion of a carding machine and apron condenser illustrating a 30 preferred form of the present invention.

Fig. 2 is a detail in front elevation of a portion of the condenser showing the driven pulley and gearing immediately connected therewith.

Fig. 3 is a side elevation of a slightly different form of condenser illustrating a 35 slightly different form of the invention.

Fig. 4 is a detail in central vertical cross section taken through the stub shaft of Fig. 2.

Fig. 5 is a diagrammatic view showing the driving and driven pulleys in reversed arrangement to that shown in Fig. 1.

Fig. 6 is a detail illustrating a different 45 arrangement of the interchangeable gearing from that shown in Fig. 1.

The present invention being concerned only with the driving mechanism, and the 50 carding machine and the condenser and their respective operations being well known and familiar to those skilled in the art, it is only necessary here to illustrate and de-

scribe a carding machine and condenser sufficiently to disclose the arrangement and 55 operation of the driving mechanism.

The carding machine is shown at one end of a main frame 1 and the condenser at the other end. It is sufficient to indicate the main shaft 2 of the carding machine, the 60 carding cylinder 3, the shafts 4 and 5 for the upper and lower doffer rings and the gears 7 and 8 respectively by which these doffer rings are driven.

The condenser is shown as of the double 65 apron type and adapted for use in connection with the two doffer system. The frame 9 of the condenser is mounted on the main frame 1 and is provided with the usual sets of shafts, aprons, rolls and gears. As illus- 70 trated in Fig. 1 an intermediate gear 10 on the shaft 11 drives through intermediate gearing both the upper and the lower sets of aprons, the upper aprons being shown at 12 and the lower aprons at 13. The same intermediate gear also through systems of 75 gearing drives the gears 14 and 15 respectively which in turn drive the doffer ring gears 7 and 8. The system of gearing between the intermediate gear and the aprons 80 and between the intermediate gear and the doffer ring gears 7 and 8 may be, and is illustrated as, of a familiar type including various change gears and, as it forms no part of the present invention, needs no further description.

A supporting bracket 16 is secured by bolts 17 and 18 to the face of the condenser frame 9 at the front thereof. This bracket presents at the side and separated from the 90 frame a plate 19 in which is formed an arc shaped slot 20 having its center of curvature located at the axis of the main shaft 2. A stub shaft 21 is adjustably mounted in the slot 20 so that in all positions of its adjustment it is at the same radial distance from the shaft 2. This stub shaft 21 is shown as provided with a collar 22 abutting the face of the bracket plate 19 and with a reduced threaded portion 23. A washer 24 on the 100 threaded portion abuts the opposite face of the bracket plate 20 and a nut 25 on the threaded portion serves to lock the stub shaft in adjusted position, the bracket plate 20 being clamped between the collar 22 and 105 the washer 24.

A driving pulley 26 is mounted on the main shaft 2 of the carding machine and a driven pulley 27 is journaled on the stub shaft 21 of the condenser and the latter 5 pulley is driven from the former by an endless flexible connector 28. In the construction illustrated in Figs. 1, 2 and 5 the pulleys are shown as having a flat face 29 and the endless flexible connector 28 is shown in 10 the form of a flat driving belt adapted to co-operate with the flat face of the pulleys but it is to be understood that other forms of pulleys and endless flexible connectors such, for example, as sprocket wheels and 15 a sprocket chain may be employed.

Movement is transmitted from the driven pulley 27 to the intermediate gear 10 through one of a plurality of interchangeable gears connected to the pulley 27 and in mesh 20 with the intermediate gear 10. Any suitable means may be employed for removably and axially connecting the interchangeable gear with the pulley. As illustrated in detail in Fig. 4 the pulley 27 is splined at 25 30 to its hub 31 which is directly journaled on the stub shaft 21. This hub at the end toward the condenser frame has a reduced portion 32 and on this reduced portion is mounted one of the interchangeable gears 33. Pins 34 entering aligned apertures in the hub and gear connect the pulley and gear together. A collar 35 is clamped by a set screw 36 to the outer end of the stub shaft 21 and thus holds the 35 pulley and interchangeable gear in place between this collar and the collar 22. A lubricating cup 37 is shown in the collar 35 and serves to distribute lubricant to the stub shaft 21.

40 There may be as many interchangeable gears as are desired. They differ only in diameter and consequently in number of teeth but each has its teeth arranged to co-operate with the teeth of the intermediate gear 10. One interchangeable gear is readily substituted for another by removing the collar 35 and the pulley 27. When an interchangeable gear has been put in place and connected to the pulley 27 on the stub 45 shaft 21, this stub shaft is then adjusted in the arc shaped slot 20 to bring the teeth of the interchangeable gear into proper co-operative relation with the intermediate gear 10 but as this arc shaped slot 20 has its center of curvature at the axis of the shaft 50 55 2 no change is necessary in the length of the endless flexible connector 28.

A still further range of adjustment is provided by having the pulleys 26 and 27 of 60 different diameters and providing means for permitting the transposition of these pulleys. That is to say, pulleys 26 and 27 are made with similar hubs so that either may be put on either the shaft 2 or the stub shaft 21. 65 In Fig. 1 the pulley 26 is shown as of larger

diameter than the pulley 27 and in Fig. 5 these pulleys are shown in transposed position.

In Fig. 1 one of the interchangeable gears 33 is illustrated and in Fig. 6 a smaller interchangeable gear 38 is shown meshing with the intermediate gear 10 and as it is smaller than the gear 33 the stub shaft 21 is shown adjusted to a lower position in the arc shaped slot 20.

75 In Fig. 3 the driven pulley 39 is shown in the form of a spocket wheel. The intermediate gear 41 corresponding to the intermediate gear 10 is shown as connected by a sprocket wheel and sprocket chain connection 42 to a small auxiliary intermediate gear 43 from which connection is made to the systems of gearing driving the upper and lower aprons. This arrangement is necessary when, as in the older types of apron condensers, the sets of aprons are located closer together so that the driving connection cannot be made directly through a single intermediate gear.

80 Various changes in the construction and arrangement of this variable speed driving mechanism may be made within the purposes and scope of the invention which is thus illustrated in simple and preferred forms.

85 With the usual type of apron condenser it has been found that by providing four interchangeable gears such as the gears 33 and 38 having 35, 38, 41 and 44 teeth respectively the speed of the doffer rings may 90 be varied from about ten to twelve and seven eighths revolutions and by having the driven and driving pulleys such as 26 and 27 of twenty one and eighteen inches diameter 95 and by transposing these pulleys, additional speeds may be obtained from about twelve and seven eighths to sixteen revolutions. With this type of condenser a range from 100 ten to sixteen revolutions for the doffer rings takes care of all grades of material running 105 from a poor quality to a high grade. Within this variation the four interchangeable gears and the transposition of the two pulleys 110 enables eight different speeds to be had thus covering in a very satisfactory manner the entire range of material from a poor to a high grade. The interchanging of the interchangeable gears and the transposition of the pulleys are readily and quickly effected without requiring any adjustment 115 or change in the flexible connector or in the systems of gearing driven by the intermediate gear.

120 Having thus described the invention, what is claimed as new, and desired to be secured by Letters Patent, is:

1. A variable speed driving mechanism for driving a condenser from a carding machine comprising a main gear journaled on the condenser for transmitting the move- 125 130

- ment to the condenser apron driving mechanism, a driving pulley journaled on the carding machine, a driven pulley journaled on the condenser, an endless flexible connector surrounding the two pulleys and acting to drive the one from the other, a plurality of interchangeable gears of different diameters, means for removably and axially connecting either of said interchangeable 5 gears and said driven pulley, and means for adjusting the axis of the driven pulley along an arc having its center at the axis of the driving pulley to permit the intermeshing of either interchangeable gear with the main 10 gear without varying the length of the flexible connector.
2. A variable speed driving mechanism for driving a condenser from a carding machine having the construction defined in 15 claim 1 in which the driven and driving pulleys are of different diameters and in which means are provided for permitting the transposition of the said pulleys further to vary the speed.
3. A variable speed driving mechanism for driving a condenser from a carding machine comprising a main gear journaled on the condenser for transmitting the movement to the condenser apron driving mechanism, a driving pulley journaled on the carding machine, a stub shaft mounted on the condenser, a driven pulley journaled on the stub shaft, an endless flexible connector surrounding the two pulleys and acting to drive the one from the other, a plurality of interchangeable 20 gears of different diameters, and means for removably and axially connecting either of said interchangeable gears and said driven pulley whereby either interchangeable gear may be made to intermesh with the main gear, without varying the length of the endless flexible connector, by adjusting the stub shaft in the said slot of the bracket.
4. A variable speed driving mechanism for driving a condenser from a carding machine comprising a main gear journaled on the condenser for transmitting the movement to the condenser apron driving mechanism, a driving pulley journaled on the carding machine, a supporting bracket on the condenser provided with an arc shaped slot having its center at the axis of the driving pulley, a stub shaft adjustably mounted 25 in the slot of the said bracket, a driven pulley journaled on the stub shaft, an endless flexible connector surrounding the two pulleys and acting to drive the one from the other, a plurality of interchangeable 30 gears of different diameters, and means for removably and axially connecting either of said interchangeable gears and said driven pulley whereby either interchangeable gear may be made to intermesh with the main gear, without varying the length of the endless flexible connector, by adjusting the stub shaft in the said slot of the bracket.
5. A variable speed driving mechanism for driving a condenser from a carding machine comprising a main gear journaled on the condenser for transmitting the movement to the condenser apron driving mechanism, a driving pulley journaled on the carding machine, a supporting bracket on the condenser provided with an arc shaped slot having its center at the axis of the driving pulley, a stub shaft adjustably mounted 35 in the slot of the said bracket, a driven pulley journaled on the stub shaft, an endless flexible connector surrounding the two pulleys and acting to drive the one from the other, a plurality of interchangeable 40 gears of different diameters, and means for removably and axially connecting either of said interchangeable gears and said driven pulley, and means for adjusting the stub shaft along an arc having its center at the axis of the driving pulley to permit the intermeshing of either interchangeable gear with the main gear without varying the length of the endless flexible connector.
6. A variable speed driving mechanism for driving a condenser from a carding machine comprising a main gear journaled on the condenser for transmitting the movement to the condenser apron driving mechanism, a driving pulley journaled on the carding machine, a supporting bracket on the condenser provided with an arc shaped slot having its center at the axis of the driving pulley, a stub shaft adjustably mounted 45 in the slot of the said bracket, a driven pulley journaled on the stub shaft, an endless flexible connector surrounding the two pulleys and acting to drive the one from the other, a plurality of interchangeable 50 gears of different diameters, and means for removably and axially connecting either of said interchangeable gears and said driven pulley, and means for adjusting the stub shaft along an arc having its center at the axis of the driving pulley to permit the intermeshing of either interchangeable gear with the main gear without varying the length of the endless flexible connector.
7. A variable speed driving mechanism for driving a condenser from a carding machine comprising a main gear journaled on the condenser for transmitting the movement to the condenser apron driving mechanism, a driving pulley journaled on the carding machine, a supporting bracket on the condenser provided with an arc shaped slot having its center at the axis of the driving pulley, a stub shaft adjustably mounted 55 in the slot of the said bracket, a driven pulley journaled on the stub shaft, an endless flexible connector surrounding the two pulleys and acting to drive the one from the other, a plurality of interchangeable 60 gears of different diameters, and means for removably and axially connecting either of said interchangeable gears and said driven pulley, and means for adjusting the stub shaft along an arc having its center at the axis of the driving pulley to permit the intermeshing of either interchangeable gear with the main gear without varying the length of the endless flexible connector.
8. A variable speed driving mechanism for driving a condenser from a carding machine comprising a main gear journaled on the condenser for transmitting the movement to the condenser apron driving mechanism, a driving pulley journaled on the carding machine, a supporting bracket on the condenser provided with an arc shaped slot having its center at the axis of the driving pulley, a stub shaft adjustably mounted 65 in the slot of the said bracket, a driven pulley journaled on the stub shaft, an endless flexible connector surrounding the two pulleys and acting to drive the one from the other, a plurality of interchangeable gears of different diameters, and means for removably and axially connecting either of said interchangeable gears and said driven pulley, and means for adjusting the stub shaft along an arc having its center at the axis of the driving pulley to permit the intermeshing of either interchangeable gear with the main gear without varying the length of the endless flexible connector.

In testimony whereof, I have signed my name to this specification.

WALTER T. PUTNAM.
